UNITED STATES PATENT OFFICE.

ALBERT KEIRLE, OF BUNKER HILL, ILLINOIS.

SILO.

1,026,516.

Specification of Letters Patent.

Patented May 14, 1912.

Application filed November 13, 1911. Serial No. 660,008.

To all whom it may concern:

Be it known that I, ALBERT KEIRLE, a citizen of the United States, residing at Bunker Hill, in the county of Macoupin 5 and State of Illinois, have invented certain new and useful Improvements in Silos; and I do hereby declare the following to be a full, clear, and exact description of the invention, such as will enable others skilled 10 in the art to which it appertains to make and use the same.

My invention relates to an improvement in silos, and particularly to weather strips interposed and connecting the abutting ends 15 of the sheathing, the object being to so connect the boards constituting the sheathing, that the joints between the boards will be practically air and water tight, and thus prevent premature decay due to the lodgment of water between the boards.

With these ends in view my invention consists in the details of construction as will be more fully described and pointed out in the claim.

25 In the accompanying drawings, Figure 1 is a view in perspective showing the meeting or abutting ends of two boards constituting a part of the sheathing or silo covering; Fig. 2 is a view in vertical section 30 through the abutting ends and interposed strip. Fig. 3 is a view in horizontal section and Fig. 4 is a view in perspective of the weather strip removed.

35 The sheathing boards used in constructing silos, are usually about one inch thick, four or five inches wide and from fourteen to sixteen feet long, tongue and grooved at the sides and placed so that each will break joints with the next adjacent boards. This 40 invention relates to means for sealing the joints between the abutting ends of the boards and it comprises a T-shaped sheet metal strip 1 seated in grooves 2 in the abutting ends of the boards 3. The grooves 2 45 are located about midway the thickness of the boards, and extend throughout their width and are adapted to snugly receive the opposite edges of the vertical member 4 of the strip 1, the horizontal member 5 of the strip resting between and separating the 50 ends of the boards, and turned down at its outer edge, as at 6, so as to cover and protect the upper edge of the lower board and shed the water falling thereon. Any water 55 passing back into the joint over the top of

the horizontal section 5 of the strip, will be blocked by the vertical section 4. The parts are however designed to fit so snugly that not only water, but air will be prevented from passing beyond the vertical section of the strip. The strip 1 is preferably made of sheet metal folded as shown, so that the vertical section will be of double thickness and the horizontal section of a single thickness of metal. The vertical section extends throughout the width of the board including the tongue 7, while the horizontal section is as long as the board is wide minus the tongue, and is grooved at its edge as at 8 adjacent the grooves in its boards so as to receive and accommodate the tongue on the next adjacent board. These strips constructed as described, not only connect and secure the abutting ends of the boards, but when applied to all the joints, render the silo practically water and air tight.

It is evident that many slight changes might be resorted to in the relative arrangement of parts shown and described without departing from the spirit and scope of my invention. Hence I would have it understood that I do not wish to confine myself to the exact construction and arrangement of parts shown and described, but

Having fully described my invention what I claim as new and desire to secure by Letters-Patent, is:—

The combination with tongue and grooved boards placed end to end, and grooved at their abutting ends, of a metal strip or member resting within the grooves in the ends of both boards and extending from the outer edges of the tongues at one side into the grooves at the other side so as to enter the tongues of the next adjacent board, and a second metal member projecting horizontally outwardly between the ends of the boards to the front thereof and turned down over the outer face of the lower board so as to form a water shed, the said second member being of slightly less length than said first mentioned member.

In testimony whereof, I have signed this specification in the presence of two subscribing witnesses.

ALBERT KEIRLE.
